SPEED REGULATING MECHANISM

Filed May 12, 1937

UNITED STATES PATENT OFFICE

2,236,669

SPEED REGULATING MECHANISM

Carl Breer, Grosse Pointe Park, and Oscar M. Raes, Detroit, Mich., assignors to Chrysler Corporation, Highland Park, Mich., a corporation of Delaware

Application May 12, 1937, Serial No. 142,144

12 Claims. (Cl. 137—152)

This invention relates to internal combustion engine driven conveyances and it has particular relation to means for regulating the maximum speed thereof.

One object of this invention resides in providing an automatic speed regulating device for use on a conveyance or vehicle which will prevent any increase in speed beyond a predetermined limit and in which, by means of the normal controls, the driver may, under emergency conditions, resume complete control of the speed of the vehicle at will.

Another object of this invention consists in providing means whereby the top limit of speed of the conveyances may be regulated from the driver's seat and may be locked in any predetermined setting.

A further object of this invention comprises providing a speed regulatory device which may be adjusted from the driver's seat, which may be locked in any adjusted position, and in which control of the speed of the vehicles may be restored to the operator by a predetermined operation of the accelerator lever thereof.

A still further object of this invention consists in providing a speed controlling and regulatory mechanism in which a conveyance may be operated up to and including a predetermined speed by operation of the accelerator against a normal accelerator lever restoring pressure and which may be operated at higher speed by operating the accelerator against a noticeably higher accelerator restoring pressure.

For a better understanding of the invention, reference may now be had to the accompanying drawing, in which:

Fig. 1 is a side elevational view of a portion of a motor vehicle showing an internal combustion engine, an accelerator lever, and an instrument panel, all provided with mechanism constructed in accordance with and embodying this invention.

Fig. 2 is an elevational view of the instrument panel illustrating a portion of the structure shown in Fig. 1.

Fig. 3 is a side view, partially in elevation and partially in cross-section, of a portion of the speed regulating device illustrated in Fig. 1, the view being taken at right angles to that of Fig. 1.

Fig. 4 is a view, partially in plan and partially in cross-section, of the structure illustrated in Fig. 3, the section being taken along the line IV—IV thereof.

Fig. 5 is a cross-sectional view of the struc-

ture illustrated in Fig. 4, the section being taken along the line V—V thereof.

Fig. 6 is a side view of the structure shown in Fig. 4 with the end plate or cover removed therefrom, thus providing a view which is quite similar to Fig. 3 but more complete and in less detail than Fig. 3.

In the drawing is shown an internal combustion engine 10 provided with a carburetor 11, and a manually operable throttle valve 12 actuated by a throttle operating lever 13 which, in turn, is operated by a V-type lever 14 through a link 15. The lever 14 is in turn actuated by a link or lever 16 which is adapted to be engaged or to constitute the usual accelerator pedal. The carburetor 11 is connected to an intake manifold 17 through a speed regulating mechanism 18. The speed regulating mechanism consists of a member which is adapted to be clamped between the carburetor 11 and intake manifold 17, with intermediate sealing gaskets, as best illustrated in Fig. 5.

The speed regulating member 18 is provided with a throat 19 within which is disposed a stationary vane 20 and a two-part movable vane 21. The vane 21 is so disposed and arranged at such angle that an increase in the velocity of the mixture of fuel and air passing through the throat 19 and passing over the vane 21 causes it to tend to move toward a partially closed position, and, unless restrained, would move to that partially closed position and permit only an extremely low fuel velocity and a resultant low speed of the automobile. The vane 21 is fixedly mounted upon a pivot rod 22, the outer end of which extends through its bearing and into a housing 23. On the outer end of the pivot rod 22 is mounted a weight member 24 which serves the purpose of preventing rapid fluctuations in the vane 21 for minor variations in the fuel flow thereover, the weight 24 and the vane 21 being both rigidly secured to the pivot rod 22 so that movement of one member is imparted thereby to the other.

As best illustrated in Figs. 3 and 4, the weight member 24 is provided with a pin 25, to which is pivotally secured a link 26 and a tension spring 27, which serves to oppose the force exerted on the vane 21 by the fuel flow thereover which tends to move it toward its closed position. It will be apparent that, as the tension on the spring 27 is varied, the velocity of the moving fuel necessary to actuate the vane 21 likewise varies therewith, so that, as the tension on the spring 27 is increased, a greater velocity flow

of fuel past the vane 21 is required before it will move toward its partially closed position. In general, this type of velocity flow regulator is old and the portion thus far described constitutes no part of the present invention.

The opposite end of the spring 27 is attached to a spring securing member 30, as best shown in Fig. 4, which is slidably mounted within a supporting member 31, which, in turn, is slidably mounted within the housing 23. The supporting member 31 is provided with an adjusting screw 32 whereby the position of the spring securing member 30 may be varied with respect to the supporting member 31, a small compression spring 33 being disposed therebetween so as to keep the spring securing member 30 as far from the end of the supporting member 31 as is permitted by the adjusting screw 32. The housing is provided with an open end 34 through which a screwdriver or other tool may be inserted in order to rotate the screw 32.

The supporting member 31 is provided on one side with a relatively short leg 35 and on the other side with a relatively longer leg 36. The longer leg 36 is adapted to abut against a cam member 37 mounted upon a rotatable shaft 38, which shaft projects outwardly through a bushing 40 in the housing 23 and is connected at its outer end to a flexible shaft 41 which extends within a casing 42 to a housing 43 mounted on the instrument board or panel 44 of the automobile. The flexible shaft 41 is provided, at its instrument board end, with a knob or dial 45 by means of which the shaft 41 and therefore the cam 37 may be rotated. The instrument board is provided with a calibrated dial 46, which may be numbered in either revolutions per minute of the engine or in miles per hour of the automobile, the latter being generally preferable, and is shown in Fig. 2. It will be apparent that, by rotating the knob 45, the cam 37 may be rotated so as to move the supporting member 31, and with it the spring securing member 30, and thus adjust the tension on the tension spring 27, which in turn controls the speed at which the automatically operated vane 21 will move toward its closed position a distance sufficient to prevent any further increase in the speed of the car. The housing 43 mounted on the instrument panel 44 is likewise provided with a locking mechanism 47 so that the adjusting mechanism may be locked in any desired predetermined speed regulating position, the advantage being that the owner of the car may thus predetermine the speed at which the car may be driven.

The shorter leg 35 of the supporting member 31 is adapted to engage an arm or stop member 50, which constitutes a portion of a supporting member 51, which is slidably mounted within the housing 23 and is secured, by means of two bolts or other securing members 52, to two externally disposed slidably mounted members 53 and 54 which have upstanding portions 55 and 56, respectively. The bolts 52 extend through openings in the wall housing 23 so as to permit the members 53 and 54, disposed outside of the housing, to move the member 51 with its stop 50 inside of the housing. A compression spring 57 is disposed within the housing 23 and in engagement with the member 51, tending to move the member 51 away from the supporting member 31. The spring 57 is materially stronger than is the tension spring 27, so that movement of the member 51 toward the end of the housing against the action of the spring 57 will require a considerably

greater force than that necessary to move against only the spring 27.

The upstanding portion 56 of the member 51 is normally held in engagement with an abutment 58 by the spring 57, thus holding the member 51, and therefore the stop member 50, in a predetermined position, thus limiting the range of movement of the supporting member 31 toward the weighted member 24. The second upstanding member 55, which is rigidly secured to the member 56, is normally disposed in spaced relationship with the abutment 58 but is adapted to be engaged by a lug or shoulder 61, mounted on the throttle actuating lever 13, so that when the lever 13 is moved to its extreme position, it engages the upstanding member 55 and moves it toward the abutment 58. This moves the stop member 50 toward the end of the housing 23 against the action of the compression spring 57 and likewise moves the supporting member 31 to increase the tension on the tension spring 27.

As best illustrated in Figs. 4 and 6, a link 65 is pivotally connected to the cam member 37 by means of a pin 66, the opposite end of the link 65 being provided with a slotted portion 67 which is adapted to encompass a pin 68 mounted on the weight member 24. The purpose of the pin and slot connection between the link 65 and the weight member 24 is to move the weight member 24, and with it, the automatically operated vane 21, a very slight amount in the direction of the closed position of the vane 21 when the cam 37 is disposed in its lowest speed adjustment, and at the same time permit independent movement of the cam and weight members under all other conditions.

Obviously, in the lowest speed adjustment, the velocity of the gasoline over the vane 21 is comparatively small and there is always some tendency for the vane to remain in its fully open position owing to the relatively light forces exerted thereon unless it is moved from its wide-open position when the cam is in its lowest speed position of adjustment.

Referring now to the structure as a whole, it will be apparent that with the adjustment on the instrument panel, when in its lowest speed, in this instance, 20 M. P. H., but which may be designed for lower speeds, the cam permits the supporting member 31 to be drawn to the extreme end of its range toward the weight member by the tension spring 27. At the same time, the stop 51 engaging the opposite leg 35 of the supporting member is likewise in its position closest to the weight member 24. Under this condition, the link 65, by means of the pin and slot construction 67, 68, holds the weight 24, and with it, the vane member 21, in a position slightly removed from its inactive position. The fuel flow over the vane 21 will increase as the manually operated throttle 12 is opened, until such time as the flow of the fuel exerts a force on the vane 21 sufficient to overcome the tension of the spring 27, at which time the vane member 21 will start to move toward its partially closed position and will so move until the amount of fuel permitted to pass thereby with the car operating at 20 M. P. H. is sufficient to create a force to balance the spring 27 and hold the vane 21 in a partially closed position regardless of how far open the throttle 12 is maintained.

If the adjustment knob 45 is now rotated to a higher speed position, for example, 40 M. P. H., it will rotate the cam 37 so as to move the supporting member 31 to a position farther from

the weighted member 34, thus increasing the tension on the spring 27. The increased tension on the spring 27 serves to return the vane 21 to its original inactive position because the velocity of the fuel flow at 20 M. P. H. is no longer sufficient to move the vane 21 against the increased tension of the spring 27. As a result, if the throttle 12 is sufficiently opened, an increased flow of fuel will flow through the throat 19 until the velocity is sufficiently great to move the vane 21 against the action of the spring 27, at which point only a sufficient amount of fuel will be permitted to pass the vane 21 to maintain the car at a speed of 40 M. P. H. In like manner, the adjusting knob 45 may be moved to any other speed position with a corresponding result. By means of the lock 41, the knob 45 may be locked in any desired position.

Assuming now that the adjusting mechanism 45 has been set at any desired figure, for example, 40 M. P. H., and due to some emergency condition it becomes imperative that the speed of the car be increased, the foot throttle is moved to its extreme position. This causes the shoulder 61 to engage the upstanding member 55 and moves 25 the stop member 50 away from the weight member 24 against the action of the relatively strong spring 57, thus moving the supporting member 31 in the housing 23 away from the weight member 24, regardless of the position of the cam 37. This increases the tension on the spring 27 beyond any tension that can be exerted thereon by the cam 37 and moves the automatically operated vane 21 back to its fully open position and holds it in that position while the car increases in speed to any desired degree beyond the speed for which the adjusting mechanism has previously been set. The force of the spring 57, however, continuously opposes holding the throttle in its extreme position and should be sufficiently greater than the tension of the spring 27 to cause a noticeable increase in the force opposing holding the throttle in its wide-open position. If desired, this spring may be sufficiently strong that an uncomfortably large amount of pressure is required to move the stop member 50 so that the driver will have a natural tendency to decrease the force on the throttle as soon as the emergency is passed.

From the foregoing description, it will be apparent that this device permits of adjusting the speed to any desired figure and permits of locking it at that position. In addition, when desired, by use of the ordinary means of controlling the speed, that is, the accelerator, the automatic adjusting device may be temporarily rendered inactive so as to provide a higher speed than that permitted by the adjusting mechanism located on the instrument panel. As soon as the pressure on the accelerator pedal is released, control 60 of the maximum speed of the vehicle is immediately restored to the automatic speed regulator in accordance with the adjustment thereof. In addition, the usual method of regulating the speed of the device, which is mounted on the 65 regulating mechanism itself, is likewise provided.

Although but one form of this invention is illustrated and but one application thereof is described in detail, it will be apparent to those skilled in the art that it is not so limited but that various minor modifications and changes may be effected therein without departing from the spirit of this invention or from the scope of the appended claims.

We claim:

1. An internal combustion engine speed governing device comprising a throttle valve adapted to be moved towards a partially closed position by the flow of fluid thereby and mounted on a movable pivot pin, a lever arm rigidly mounted on said pin, a spring connected to said lever arm and adapted to yieldingly resist movement of said throttle valve towards the partially closed position, a slidable member adapted to constitute 10 a support for the opposite end of said spring, a rotatable cam member disposed in engagement with said slidable member and adapted to move it slidably to vary the force exerted by said spring on said lever arm, a link pivotally mounted on said cam, a lost motion connection between said link and said lever arm, and means for rotating said cam.

2. An internal combustion engine speed governing device comprising a throttle valve directly responsive to and adapted to be moved towards a partially closed position by the flow of fluid thereby and mounted on a movable pivot member, a rotatable member comprising a lever arm rigidly mounted on said pivot member, a housing enclosing said rotatable member, a supporting member slidably mounted in said housing member, a spring securing member slidably mounted in said supporting member, means for adjusting said spring securing member with respect to said supporting member, a spring secured at one end of said spring securing member and at the other end to said rotatable member and adapted to yieldingly resist movement of said throttle valve towards the partially closed position, and stop means adapted to limit the movement of said supporting member in said housing.

3. An internal combustion engine speed governing device comprising a throttle valve adapted to be moved towards a partially closed position by the flow of fluid thereby and mounted on a movable pivot member, a rotatable member comprising a lever arm rigidly mounted on said pivot member, a housing enclosing said rotatable member, a supporting member slidably mounted in said housing member, a spring securing member slidably mounted in said supporting member, means for adjusting said spring securing member with respect to said supporting member, a spring secured at one end to said spring securing member and at the other end to said rotatable member and adapted to yieldingly resist movement of said throttle valve towards the partially closed position, stop means adapted to limit the movement of said supporting means in said housing towards said spring, and means for moving said stop means.

4. In a fuel system for an internal combustion engine having a fuel mixture passage, speed governing means comprising a manually operated throttle valve in said passage and mechanism for operating the same, a second throttle valve in said passage adapted to be moved towards a partially closed position by the flow of fluid thereover and mounted on a movable pivot member, a weighted member mounted on said pivot member and movable with said second throttle valve, a housing adapted to enclose said weighted member, a supporting member slidably mounted in said housing, a spring securing member slidably mounted in said supporting member, means for adjusting said spring securing member with respect to said supporting member, a spring secured at one end to said spring securing member and at the other end to said weighted member to yieldingly oppose movement of said second

throttle valve towards its partially closed position, a stop member adapted to limit the movement of the supporting member towards said spring, and means for moving said stop member comprising a member disposed in the path of the mechanism for operating the manually operated throttle valve.

5. In a fuel system for an internal combustion engine having a fuel mixture passage, speed governing means comprising a manually operated throttle valve in said passage and mechanism for operating the same, a second throttle valve in said passage adapted to be moved towards a partially closed position by the flow of fluid thereover and mounted on a movable pivot member, a weighted member mounted on said pivot member and movable with said second throttle valve, a housing adapted to enclose said weighted member, a supporting member slidably mounted in said housing, a spring securing member slidably mounted in said supporting member, means for adjusting said spring securing member with respect to said supporting member, a spring secured at one end to said spring securing member and at the other end to said weighted member to yieldingly oppose movement of said second throttle valve towards its partially closed position, a stop member adapted to limit the movement of the supporting member towards said spring, and means for moving said stop member comprising a member disposed in the path of the mechanism for operating the manually operated throttle valve at the end of its normal range of movement.

6. In a fuel system for an internal combustion engine having a fuel mixture passage, speed governing means comprising a manually operated throttle valve in said passage and mechanism for operating the same, a second throttle valve in said passage adapted to be moved towards a partially closed position by the flow of fluid thereover and mounted on a movable pivot member, a weighted member mounted on said pivot member and movable with said second throttle valve, a housing adapted to enclose said weighted member, a supporting member slidably mounted in said housing, a spring securing member slidably mounted in said supporting member, means for adjusting said spring securing member with respect to said supporting member, a spring secured at one end to said spring securing member and at the other end to said weighted member to yieldingly oppose movement of said second throttle valve towards its partially closed position, a stop member adapted to limit the movement of the supporting member towards said spring, a relatively strong spring adapted to oppose movement of said stop member away from said first mentioned spring, and means for moving said stop member away from said first mentioned spring comprising a member disposed in the path of the mechanism for operating the manually operated throttle valve adjacent the end of its range of movement.

7. In an internal combustion engine speed governing mechanism, a manually operated throttle for said engine, means for actuating said throttle, a speed governing device comprising a second throttle valve adapted to be moved towards a partially closed position by the flow of fluid thereover and mounted on a movable pivot member, a weight member mounted on said pivot member, a housing enclosing said weight member, a supporting member slidably mounted in said housing, a spring securing member slidably mounted on said supporting member, a spring mounted on said supporting member, a

secured at one end to said spring securing member and at the other end to said weight member and adapted to yieldingly resist movement of said throttle valve towards the partially closed position, a member in threaded engagement with said supporting member and operatively connected to said spring securing member to adjust the spring securing member with respect to the supporting member, a cam mounted in said housing and adapted to engage said supporting member, remote control means for rotatively adjusting said cam, a stop member disposed within said housing and adapted to limit the movement of said supporting member towards said spring, and means disposed within the path of the first throttle actuating means and adapted to move said stop member.

8. In an internal combustion engine speed governing mechanism, a manually actuated throttle valve control mechanism, a speed governing device comprising a second throttle valve adapted to be moved towards a partially closed position by the flow of fluid thereover and mounted on a movable pivot member, a weight member mounted on said pivot member, a housing enclosing said weight member, a supporting member slidably mounted in said housing, a spring securing member slidably mounted on said supporting member, a spring secured at one end to said spring securing member and at the other end to said weight member and adapted to yieldingly resist movement of said throttle valve towards the partially closed position, a member in threaded engagement with said supporting member and operatively connected to said spring securing member to adjust the spring securing member with respect to the supporting member, a cam mounted in said housing and adapted to engage said supporting member, remote control means for rotating said cam and for locking said cam in its rotated position, a stop member disposed within said housing and adapted to limit movement of said supporting member towards said spring, and means adapted to move said stop member away from said spring, said last mentioned means being so arranged with respect to said manually actuated throttle valve control mechanism as to be actuated thereby only under predetermined conditions.

9. A fuel system for an internal combustion engine including a fuel mixture passage for supplying a fuel mixture to said engine, a normal throttle valve in said passage, manually operable control mechanism for actuating said valve, a second throttle valve in said fuel mixture passage between said normal throttle valve and said engine and adapted to be moved toward a partially closed position by the flow of fuel in said passage, means adapted to yieldably resist movement of said second mentioned valve by fuel flow, and means responsive to actuation of said manually operable control mechanism beyond a predetermined portion of its range of valve opening movement for increasing the resistance of said yielding means to operation of said second mentioned valve by the action of fluid flow.

10. A fuel system for an internal combustion engine including a fuel mixture passage for supplying a fuel mixture to said engine, a normal throttle valve in said passage, manually operable control mechanism for actuating said valve, a second throttle valve in said fuel mixture passage between said normal throttle valve and said engine and adapted to be moved toward a partially closed position by the flow of fuel in said

passage, a relatively light spring adapted to yieldably resist movement of said second mentioned valve by fuel flow, manually operable means operable to establish the predetermined resistance of said yieldable means to operation of said second throttle valve by fuel flow, means responsive to actuation of said manually operable control mechanism beyond a predetermined portion of its range of valve opening movement for increasing the predetermined resistance of said yieldable means to fluid flow operation of said second valve as established by said manually operable means, and a relatively heavy spring operable to oppose variation of said predetermined resistance.

11. In a throttle control mechanism for an internal combustion engine, a throttle valve for said engine, a manually operable throttle actuating member for said valve, an automatically operated throttle mechanism adapted to normally assume control of the maximum speed of the engine under predetermined conditions including a valve and a resilient element opposing closure thereof, and means responsive to actuation of said throttle actuating member during a portion of its normal range of throttle opening move- 15 20 25

ment and acting upon said resilient element for varying its opposition to closure of said second mentioned valve and raising the speed of the engine at which said automatic mechanism assumes control of the maximum speed of the engine.

12. In a throttle control mechanism for an internal combustion engine, a throttle valve, a manually operated throttle control for said valve, an automatically operated throttle mechanism adapted to control the maximum speed of said engine and adapted to become operative under certain predetermined conditions of speed of said engine including a valve and a spring for opposing closure of said valve, said spring being conditionable to increase the predetermined speed conditions of the engine under which said automatic mechanism becomes operative, and means disposed in the path of movement of said manually operated throttle control and responsive to operation of said control during a portion of its normal throttle opening range of movement for conditioning said spring as aforesaid.
